Primary Examiner—Carol Rademaker*(74) Attorney, Agent, or Firm*—Davis Wright Tremaine LLP;
George C. Rondeau, Jr.(57) **CLAIM**

The ornamental design for a flask, as shown and described.

DESCRIPTION

FIG. 1 is a top, rear and right side perspective view of a flask showing my new design;

FIG. 2 is a front elevational view thereof;

FIG. 3 is a rear elevational view thereof;

FIG. 4 is a left side elevational view thereof, the right side elevational view being a mirror image; and,

FIG. 5 is a top plan view thereof.

The broken lines shown in the drawing views are included for the purpose of showing environmental structure that forms no part of the claimed design.
